DESIGN.

E. T. CURRAN.

GUARD FOR RADIATORS OF MOTOR VEHICLES.

APPLICATION FILED JUNE 9, 1920.

56,275.

Patented Sept. 14, 1920.

INVENTOR:

Edward T. Curran

By his Attorney

John O. Seifert

UNITED STATES PATENT OFFICE.

EDWARD T. CURRAN, OF DETROIT, MICHIGAN.

DESIGN FOR A GUARD FOR RADIATORS OF MOTOR-VEHICLES.

56,275.

Specification for Design.

Patented Sept. 14, 1920.

Application filed June 9, 1920. Serial No. 387,753. Term of patent 14 years.

To all whom it may concern:

Be it known that I, EDWARD T. CURRAN, a citizen of the United States, residing in the city of Detroit, in the county of Wayne and State of Michigan, have invented a new, original, and ornamental Design for a Guard for Radiators of Motor-Vehicles, of which the following is a specification, reference being had to the accompanying drawing, forming a part thereof.

The figure is a perspective view of a guard for radiators of motor vehicles, showing the design.

I claim:

The ornamental design for a guard for radiators of motor vehicles, as shown.

EDWARD T. CURRAN.
